UPPER SMOOTHING MACHINE

George Francis Ryan, Peabody, Mass., assignor to
 United Shoe Machinery Corporation, Borough
 of Flemington, N. J., a corporation of New
 Jersey

Application May 25, 1939, Serial No. 275,622

16 Claims.

(Cl. 12—51)

This invention relates to machines for treating shoe uppers to improve their shape and appearance. When shoes have been substantially completed, for example when they reach the packing room, the uppers are often somewhat wrinkled and the rim portion of the uppers about the foot opening curled slightly outward showing the top edge of the linings.

It is an object of this invention to give the uppers a more presentable appearance by smoothing and shaping them and by pressing the top edge portion of the uppers inwardly over the top of the linings so as partly or wholly to conceal the top edge of the linings. To this end the illustrated machine is provided with a shoe supporting form, presser members which are arranged for movement into contact with an upper on the shoe supporting form, and means for causing relative bodily movement of the shoe supporting form and the presser members so that the latter will move over the surface of a shoe upper on the supporting form with a wiping action which will remove wrinkles and press the top edge portion of the upper inwardly over the top edge of the lining. To increase the effectiveness of the upper shaping operation, means are provided for heating the shoe form so that it will shrink the upper lining, thereby reducing the area of the lining relatively to the upper and facilitating the overlapping of the top edge of the lining by the top edge portion of the upper.

It is a further object of this invention to control the pressure applied to the upper by the presser members during the smoothing and shaping operation. In the illustrated embodiment of my invention, this control is effected by a pattern which is disposed in cooperative relation with the mounting means for the presser members, the arrangement being such that during the relative bodily movement of the shoe supporting form and the presser members the latter are moved toward and away from the shoe supporting form in accordance with the variations in the heightwise contour of that form.

These and other features of the invention will appear more fully from the following detailed description when read in connection with the accompanying drawings and will be pointed out in the appended claims.

In the drawings:

Fig. 1 is a front elevation of a machine embodying my invention;

Fig. 2 is a side elevation of the machine shown in Fig. 1, some parts being broken away and

others omitted for the purpose of illustrating more clearly the underlying parts;

Fig. 3 is a vertical transverse section on a larger scale, of a portion of the machine shown in Fig. 1, illustrating the position of the pressing mechanism at the beginning of an upper shaping operation;

Fig. 4 is a view similar to Fig. 3 showing the position of the pressing mechanism at a later stage in the operation;

Fig. 5 is a sectional view on an enlarged scale illustrating the action of the presser pads on the top edge of an upper during the upper shaping operation;

Fig. 6 is a diagrammatic plan view showing a convenient arrangement of three machines about a central position so that they can be operated by one operator;

Fig. 7 is a view looking down on one of the 20 presser pads showing successive parts of the pad broken away to illustrate the construction of a pad and its carrier;

Fig. 8 is a perspective view of the form carrier, and

Fig. 9 is a perspective view of one of the elliptical pad springs.

The illustrated machine is provided with a table 10 (Fig. 1) which carries the operating mechanism and also supports a number of spare shoe forms 121 which will be referred to later. Mounted on the rear end of the table 10 (Fig. 2) is a supporting bracket 12 for a form carrier 14 (Fig. 8). The bracket 12 consists of a base plate 16 bolted to the table 10 and an upstanding face plate 18 which is braced by a rearwardly extending rib 20 connected to the base plate 16. The face plate 18 has formed therein a longitudinal recess 22 (Fig. 1) for the reception of the form carrier 14, ways being formed at the sides of the recess by plates 23, 24 which are fastened to opposite sides of the face plate 18 and project over the side walls of the recess thereby forming grooves in which the edges of the form carrier 14 slide.

45 Mounted on the form carrier 14 (Figs. 2 and 8) are an upper form support 26 having a forwardly extending arm 28 and a lower form support 30 having a forwardly extending arm 32. Each of the arms 28 and 32 has an undercut 50 groove 34 formed in its upper surface for the reception of the base portion of a shoe form. Complementally shaped shoe forms 46, 48, i. e., a right and left, are mounted on the arms 28, 32, these forms having wedge shaped bases shaped for a sliding fit in the grooves 34 so that they

may readily be interchanged; or if desired both can be removed and replaced by forms of a different size or style.

The form carrier 14 is raised and lowered for a purpose which will hereinafter be described, by a bell crank lever (Figs. 1 and 2) fulcrumed on the frame 12 and having a forwardly extending operating arm 36 and a rearwardly extending arm 37 which is connected to the form carrier 14 by a link 38, the connection between the lever arm 37 and the link 38 forming a toggle. The link 38 is pivoted to a rearwardly extending lug 40 on the form carrier 14, the lug 40 projecting through an elongated opening 42 in the recessed portion 22 of the face plate 18 (Figs. 1 and 2). The heightwise dimension of the elongated opening 42 is sufficient to permit the desired up and down movement of the form carrier 14. Downward movement of the form carrier 14 is limited by a stop screw 45 mounted on the table 10 beneath the central portion of the form carrier 14 (Fig. 1).

Attached to the forward portion of the table 10 (Fig. 2) in front of the bracket 14 is a supporting frame upon which presser pads 43, 44 are mounted for smoothing and shaping operations by contact with a fractional portion of the height of the upper U of a shoe carried upon the upper shoe form 46 and these operations are extended heightwise by a relative movement between the shoe form and the pads. The supporting frame consists of a pair of inverted U-shaped members 50, 52 (Figs. 1 and 2) which are fastened to the table 10 by bolts 54 and are braced at their upper ends by interconnecting tie rods 56, 58. Mounted on the supporting members 50, 52 between the upper and lower shoe forms 46, 48 (Fig. 2) is a rod 60 upon which is fulcrumed a plurality of pairs of crossed, pad-carrying levers 62, 64. Each of these levers has an elliptical spring 76 (Fig. 9) connected to its upper end adjacent to the upper shoe form 46 (Fig. 3), a series of these springs together with their covering material forming each of the presser pads 43, 44. At their lower ends the levers 62, 64 have inwardly extending projections 88, 90 upon which are mounted sensing rollers 89, 91 which are normally held in engagement with the sides of the lower form 48 by springs 92, 94, these springs being connected at one end to the lower portions of the levers 62, 64 (Fig. 1) and at their other end to eye bolts 96 fastened to the table 10. Due to the crossed arrangement of the levers 62, 64, the rollers 89 or 91 on the lower end of each lever will contact that portion of the surface on the lower form 48 which corresponds to the portion of the surface on the upper form 46 which is operated upon by the spring 76 on the upper portion of the corresponding lever (Fig. 3). Thus, the roller 91 on the lever 64 will engage the outer surface of the lower form 48, which may be a right, while the spring 76 on the upper portion of that lever presses against the outer surface of the upper form 46 which would be a left. In a like manner the roller 89 on the lower end of the lever 62 and the spring 76 on the upper portion of this lever will engage the inner surfaces of the lower and upper forms, respectively.

The presser pads 43, 44 are formed by the entire group of elliptical springs 76 on the levers 62, 64, respectively, each group of springs being encased in a strip of padding material 82 and a pad cover 84 (Figs. 3 and 7) which may be of leather or other desired material. The edges

of the padding material 82 and the pad cover 84 are notched between the springs 76 to allow the pads to curve in a lengthwise direction lengthwise of a shoe so as to conform to the upper form 46. As the connections between the elliptical springs 76 and the levers upon which they are mounted are the same, only one connection will be described and like numerals will be given to all of the corresponding connecting parts. Referring to Fig. 3, it will be seen that the elliptical spring 76 is mounted on a supporting member which consists of a head 68 and a spindle 66, the spindle being slidably mounted in an opening in the lever 62. The depending ends of the spring 76, the padding material 82 and the pad cover 84 are fastened to the head 68 of the supporting member by bolts 86 which extend through the head 68 and clamp them against the sides of the head. When the presser pad is out of contact with the upper form, as when it is in the position shown in Fig. 1, the supporting member is urged inwardly away from the lever by a light spring 78 which surrounds the spindle 66 and is interposed between the head 68 and the adjacent face of the lever 62, inward movement of the head 68 being limited by a washer 72 which is retained on the projecting end of the spindle 66 by a cotter pin 74. Total collapse of the elliptical springs 76 when the pads 43, 44 are pressed against a shoe upper on the form 46 is prevented by a mat of felt or like backing material 87 which is inserted in the openings in the springs on each group of levers 62, 64.

The pressure applied by the pads 43, 44 to the upper of a shoe on the form 46 is regulated by the position of the levers 62, 64. For example, when the lever 62 is in the position shown in Fig. 3 the spring 76 is fully compressed and the spring 78 is somewhat distorted. Further movement of the lever 62 inwardly toward the form 46 increases the pressure applied to the side of the form while movement away decreases it. Due to the arrangement of the levers 62, 64 and the lower form 48 just described, the pressure applied to the upper of a shoe on the upper form 46 is maintained substantially constant throughout the operation of the machine because as the form 46 moves past the spring 76 on the upper end of a lever, a corresponding portion of the surface of the lower form 48 moves past the sensing roller 89 or 91 on the lower end of that lever causing the lever to move outwardly or allowing it to move inwardly under the urging of the spring 92 or 94 thus varying the position of the lever relatively to the upper form in accordance with variations in the heightwise shape of that form.

The pads 43, 44 also conform to the lengthwise contour of the upper form 46 due to the fact that each of these pads is supported by a plurality of the levers 62 or 64 which are individually positioned by their rollers 89 or 91, the rollers in turn cooperating with and being positioned by different longitudinal sections of the lower form 48.

It will be noted from an inspection of Figs. 3 and 4 that the shape of the lower form 48 is such that when the form carrier 14 is in its lower position the lower form cooperates with the springs 92, 94 to hold the form carrier in that position, and after the initial upward movement of the carrier the lower form assists the further upward movement of the form carrier. Thus, when the form carrier 14 is in its lower

position, as shown in Fig. 3, the rollers 89, 91 are in engagement with the converging surfaces on the upper portion of the form 48 and the inward pull of the springs 92, 94 will act through the rollers 89, 91 to exert a downward pressure on the form 48. As the form carrier 14 is moved upward by the lever 36 the rollers ride first outwardly over the bulges formed on the sides of the lower form 48 and then inwardly on the converging surfaces which taper toward the base. As they ride inwardly on the converging surfaces the springs 92, 94 act through the rollers 89, 91 to exert an upward pressure on the form 48 which assists its upward movement.

The upper and lower forms 46, 48 are heated by resistance units 113, 114 in the form carrying arms 28, 32, the units being connected to a source of power by leads extending through conduits 116, 118 (Fig. 2) to a terminal box 120 mounted on the bracket 12. The heat from the upper form 46 causes the lining of a shoe on that form to shrink and thereby assists the pads 43, 44 in shaping the top edge of the shoe around the foot opening. This action can best be understood by referring to Fig. 5 where it will be seen that the shrinking action of the heated form 46 will cause the lining L to contract in an upward direction inasmuch as that is the only direction in which it can move since it is held tightly against the form by the pressure of the pads 43, 44. The upward movement of the lining L will act through the stitching S to pull the upper U inwardly. This will assist the pressing action of the pad on the top edge of the upper U. The lower form 48 is heated to approximately the same temperature as the upper form 46 so that the lower form will be ready for immediate use when the two are interchanged.

Spare forms 121 of different sizes are carried on a supporting bar 122 (Figs. 1 and 2) which is connected at its ends to legs 124, 126 of the table 10. These forms are heated by a resistance unit 128 which is connected to a source of power by leads extending through a conduit 130 to the terminal box 120 (Fig. 2), so that they are always ready for use without delay.

The levers 62, 64 and the pads 43, 44 carried by them are moved backwardly away from the forms 46, 48 by an elongated cam 100 which is rotatably mounted on the supports 50, 52 and is located between substantially parallel faces 102, 104 (Fig. 3) on the levers 62, 64, the arrangement being such that when the cam 100 is in a horizontal position the levers and pads are held away from the forms. The cam 100 is rotated in a clockwise direction, as viewed in Fig. 1, to its horizontal position by a link and lever system which consists of a bell crank lever 106 (Fig. 1) fulcrumed at 105 to the support 50 and a link 108 which is connected at 110 to the lever 106 and at 111 to a crank 112 fastened to the cam 100. The adjacent ends of the lever 106 and the link 108 are provided with shoulders 107, 109 arranged for engagement with each other upon the depression of the lever 106, the shoulders engaging one another to prevent further rotation of the lever 106 shortly after the center of the pivot 110 passes the line of centers of the pivots 105, 111 at which point the elongated portion of the cam 100 will be in the horizontal position shown in Fig. 1 where it will hold the levers away from the forms 46, 48.

In shoe shaping operations it is frequently desirable to press the shoe tongues at the same time that the upper shaping operations are car-

ried out so as to remove wrinkles in the tongues which are generally due to the pressure of the lacing thread used to hold the eyelet flies together during the lasting operation. To accomplish this, the forms may be provided with a thin plate 132 (Fig. 2) which can be inserted between the tongue and the shoe fly when a shoe is being placed on the form so that it will be pressed against the tongue by the pads as they are pressing against the sides and eyelet flies.

The efficiency of the shaping operation will be materially increased if the form carrier is allowed to remain for a short time in its upper position shown in Fig. 4 where heat and pressure are applied to the upper and lining of a shoe on the upper form, as this will set the upper material in the desired shape. This result may be obtained by grouping a number of machines such as A, B, and C (Fig. 6) about a central position so that an operator may stand in the center and successively operate upon the various machines, leaving a shoe in the first machine until after a shoe has been placed in the last machine of the group. If desired, alternate machines may be provided with rights and lefts of the same size so that it will not be necessary to interchange upper and lower forms in the machines.

To operate the machine, assuming that it is in the condition shown in Fig. 1, a right and a left form of a desired size are taken from the rack 122 and are slid onto the form supporting arms 28, 32 on the form carrier 14. A shoe is then placed on the upper form 46 and the lever 106 is moved in a counterclockwise direction as viewed in Fig. 1, thus moving the elongated portion of the cam 100 to a vertical position (Fig. 3) and allowing the springs 92, 94 to move the pads 43, 44 inwardly into engagement with the shoe upper adjacent to the sole line. The arm 36 is then depressed, raising the form carrier 14 and forcing the upper form 46 past the pads 43, 44 so that the pads exert a dragging or wiping action on the upper in a downward direction toward the foot opening. This wiping action removes wrinkles, creases and the like from the upper and as the edge of the foot opening is moved past the pads the top edge of the upper is pulled over the top of the lining thereby hiding the latter (Fig. 5). The heat from the shoe receiving form 46 causes the lining L to shrink and pull the upper U inwardly thereby assisting the down-wiping action of the pads 43, 44 which pulls the top edge of the upper over the top of the lining. After the shoe has remained in this position a short time to allow the upper to set in its new shape, the arm 106 is moved in a clockwise direction to move the elongated portion of the cam 100 back to the horizontal position shown in Fig. 1. This movement of the cam 100 forces the levers 62, 64 and the pads and rollers away from the forms so that the shoe which has been shaped can be removed from the upper form 46. The forms are then lowered and another shoe placed on the upper form. If desired, the cycle of operation may be varied by placing a shoe on the upper form 46 while it is in its upper position, then lowering the form carrier 14, moving the pads into engagement with the shoe upper and repeating the operations described above.

Having thus described my invention, what I claim as new and desire to secure by Letters Patent of the United States is:

1. In a shoe upper shaping machine, a shoe

support, a pad arranged for engagement with a fractional portion of the height of the upper of a shoe on the support, means for pressing the pad against the upper of a shoe on the support, and means for causing relative bodily movement of the shoe support and the pad when the latter is in engagement with the upper to cause the pad to move over at least a major portion of the heightwise extent of the surface of the upper with a wiping action in the direction of the shoe opening.

2. A shoe upper shaping machine comprising a support, a shoe form mounted on the support for movement in a heightwise direction, pads adjacent to said support constructed and arranged for movement into engagement with a shoe upper on the form, and means for moving the shoe form in a heightwise direction when the pads are in engagement with the sides of the shoe upper to cause the pads to exert an upwiping action on the upper in the direction of the foot opening.

3. A shoe upper shaping machine as defined in claim 2 having resilient means for urging the pads toward the shoe form.

4. A shoe upper shaping machine as defined in claim 2 in which the pads are carried on pivoted arms and having means for moving the pivoted arms away from the shoe form and for holding them out of engagement with the shoe form to permit the interchange of shoes on the form.

5. A shoe upper shaping machine comprising a support, a shoe form mounted on the support for movement in a heightwise direction relatively to the support, pads adjacent to the shoe form arranged for engagement with the upper of a shoe on the form, means comprising pivoted arms for supporting said pads, resilient means for urging the arms toward the shoe form, and means for moving the pivoted arms away from the shoe form against the resistance of the resilient means to move the pads out of engagement with the shoe form to permit the interchange of shoes on the form.

6. In a shoe upper shaping machine, a shoe support, a pad arranged for engagement with the upper of a shoe on the shoe support, a carrier for said pad, means for causing relative heightwise movement between the shoe support and the pad when the pad is in engagement with a shoe upper thereby causing the pad to effect a wiping action on the upper, and means for adjusting the position of the pad carrier relatively to the shoe support during the relative movement between the pad and the shoe support to compensate for changes in the contour of the shoe support.

7. In a shoe upper shaping machine, a shoe form, a pad arranged to wipe the upper of a shoe on the form in the direction of the foot opening, and a pattern for controlling the position of the pad during the wiping action.

8. In a shoe upper shaping machine, a shoe support, a pad mounted for movement into engagement with the upper of a shoe on the support, means for causing relative movement of the shoe support and the pad to move the area of engagement between the pad and the shoe upper in the direction of the foot opening, and a pattern for positioning the pad while in contact with the shoe upper.

9. A shoe upper shaping machine comprising a shoe form, pads mounted for movement into engagement with the upper of a shoe on the shoe form, carriers for the pads mounted for movement toward and away from the shoe form,

means for moving the shoe form transversely of the pads when the latter are in engagement with the upper of a shoe on the form, and a second form disposed in cooperative relation with the pad carriers for controlling the pressure exerted by the pads against the upper of the shoe on the shoe form.

10. A shoe upper shaping machine comprising a shoe form, pads mounted for movement into engagement with the upper of a shoe on the shoe form, pivoted carriers for the pads, means for moving the shoe form in a direction heightwise of the form when the pads are in engagement with the shoe upper on the form, and a second

15 form disposed in cooperative relation to the pad carriers for controlling the pressure exerted by the pads against the shoe upper during the movement of the first mentioned shoe form past the pads.

20 11. A shoe upper shaping machine comprising spaced pads, pivoted carriers for the pads, said carriers having sensing members thereon, a shoe form positioned for engagement by the pads, a complementally shaped form positioned for engagement by the sensing members, and means for moving said forms relatively to the pads and the sensing members respectively whereby the pads will exert a wiping action on the upper of a shoe on the shoe form and the complementally 25 shaped form will cooperate with the sensing members to control the pressure exerted by the pads on the upper.

30 12. A shoe upper shaping machine as defined in claim 11 having springs arranged to hold the sensing members in engagement with the complementally shaped form and cam means for moving the pads back out of engagement with the shoe form.

35 13. In a shoe upper shaping machine, a shoe form, a complementally shaped form adjacent the shoe form, pads arranged for engagement with the upper of a shoe on the shoe form, a plurality of pivoted carriers for the pads, said carriers having sensing members disposed for engagement with different sections of the complementally shaped form whereby the pads are conformed to the lengthwise configuration of the shoe form, and means for causing relative movement of the forms and the pads whereby the 40 pads will exert a wiping action on the upper of the shoe on the shoe form and the complementally shaped form will cooperate with the sensing members to control the pressure exerted by the pads on the upper.

45 14. A shoe upper shaping machine comprising a support, a form carrier mounted on the support for movement in a heightwise direction, complementally shaped forms mounted on the form carrier at spaced points, pads arranged for engagement with one of the forms, pad supporting members pivoted on the support between the forms, said pad supporting members being connected to the pads on one side of their pivot and being constructed and arranged for sliding engagement with the form on the other side of their pivot whereby the latter form will control the position of the pad supporting members during the heightwise movement of the form carrier.

50 15. A shoe upper shaping machine comprising a support, a form carrier mounted on the support for movement in a heightwise direction, forms mounted on the carrier at spaced points, pads arranged for engagement with one of said forms, pad supporting members pivoted between the forms, said pad supporting members being ar-

ranged for engagement with and control by the other form, and means for moving the form carrier in a heightwise direction.

16. A shoe upper shaping machine comprising an adjustably mounted form carrier, forms mounted on the form carrier at spaced points, pads arranged for engagement with one of said

forms, and a plurality of pivoted pad supporting members for each pad arranged for engagement with and control by lengthwise spaced sections of the other form whereby the pads are conformed to the configuration of the pad engaged form.

GEORGE FRANCIS RYAN.
